DESIGN FOR A SEWING CABINET

Marley O. Miller, Brazil, Ind.

Application April 15, 1935, Serial No. 56,379

Term of patent 7 years

To all whom it may concern:

Be it known that I, Marley O. Miller, a citizen of the United States, residing at Brazil, in the county of Clay and State of Indiana, have invented a new, original, and ornamental Design for a Sewing Cabinet, of which the following is a specification, reference being had to the accompanying drawing, forming part thereof.

In the drawing, Fig. 1 is a perspective view of a sewing cabinet, showing my new design; and Fig. 2 is a cross section thereof.

I claim:

The ornamental design for a sewing cabinet, as shown.

MARLEY O. MILLER.
